UNITED STATES PATENT OFFICE.

JOHN T. COWLES, OF CHICAGO, ILLINOIS.

BEDCLOTHES-HOLDER.

1,051,560.

Specification of Letters Patent. Patented Jan. 28, 1913.

Application filed April 5, 1909. Serial No. 487,985.

To all whom it may concern:

Be it known that I, JOHN T. COWLES, a citizen of the United States, residing at Chicago, in the county of Cook and State 5 of Illinois, have invented certain new and useful Improvements in Bedclothes-Holders, of which the following is a full, clear, and exact specification.

This invention relates to improvements in 10 bed clothes holders. Its object is to make a simple and efficient bed clothes holder that will be convenient in use and economical in manufacture.

To the attainment of these ends and the 15 accomplishment of other new and useful objects as will appear, the invention consists in the features of novelty in the construction, combination and arrangement of the several parts, hereinafter more fully de- 20 scribed and claimed, and shown in the accompanying drawings, illustrating an exemplification of this invention, and in which;—

Figure 1 illustrates a perspective view of 25 the device applied to the foot or side rail of a bedstead, the view being from the exterior of the bedstead; Fig. 2 is a vertical section of the device, showing the jaws open to receive the bed clothes; Fig. 3 is a vertical section of the device applied to a bed- 30 stead, showing the clothes fastened thereby; and Fig. 4 is a plan view showing the curvature that may be used in one or both of the jaws for the purposes hereinafter described.

This device comprises, generally speaking, two jaws 1, 2, preferably made of angle iron of the form shown, but which, of course, might readily be made of other material and of other shape. These jaws are 35 designed to be movable with relation to each other for the purpose of receiving the bed clothes between them and securely holding them until it is desired to remove them. To accomplish this result, one of the jaws, preferably 40 1, being the inner one, is mounted on the top of the upright standards 3, 4, which are provided with suitable means on their lower extremities for attachment to a bedstead. Hooks 5, 6 are shown on the lower 45 extremities, and hook bolts 7, 8, provided with winged nuts and passing through the standards, serve as one means for accomplishing this result. Two or more holes for hook bolts 7, 8 may be formed in stand- 50 ards as indicated by 10, thus allowing the device to be attached to angles varying in

size. The upper ends of the members 3, 4 are preferably deflected inwardly, in order to bring the stationary jaw 1 firmly into contact with the mattresses and thus insure firm 60 contact between the mattresses and bed clothing.

The movable jaw 2 is mounted on members 11, 12, which are pivoted to upright members 3, 4 at 13, 14. The lower ends of 65 11, 12 extend below pivotal points 13, 14 and to them are pivotally secured the controlling links 15, 16 at 17, 18. These links are operatively connected to levers 19, 20 at 70 21, 22, which levers are pivoted to upright 70 members 3, 4 at 23, 24. The handle portions of levers 19, 20 may be deflected outwardly to make them more accessible to the operator.

By reference to Figs. 2 and 3, the opera- 75 tion and control of the jaws is best understood. When the lever 19 is raised upwardly, the link 15 operates to open the jaws. After the clothing is inserted, the downward movement of the lever likewise 80 closes the jaws. In order to securely fasten the clothing, the jaws are locked together when the lever 19 is in its lowermost position, or approximately in contact with the angle-iron member 25, to which the device 85 is shown attached, by reason of the fact that as the lever 19 is moved downwardly, the line connecting the pivotal points 17, 21 on link 15 approaches the pivotal point 23 of the lever 19, and in the lowermost position 90 passes below the pivotal point 23. When the parts are in this position, as shown in Fig. 3, it will be seen that pressure tending to open the jaws 1, 2 will pull the lever downward and against the member 25, so 95 locking the jaws that it is necessary for the lever to be moved upwardly until the line of the pivotal points on the link again passes above the pivotal point 23 in order to separate the jaws and release the clothing. The 100 form shown of fastening the angle jaws to the supporting members is preferred. The outer edge of the leg of one angle jaw enters the angle between the legs of the other jaw and co-operates therewith to hold 105 the bed clothing. This permits the fastening of the supporting members to the outsides of the legs, and at the same time presents the most satisfactory holding surfaces to the bed clothing.

As a means of securing uniform tension or pressure on the bed clothing throughout 110

the entire length of the clamping jaws, one or both of the jaws may be given a gentle curve near the middle, which curve should be deflected toward the other jaw in the 5 manner shown by the full lines 26, 27, in Fig. 4. The jaws 1, 2, being supported near the ends and being of considerable length, it is evident that without this curvature, on account of the flexibility of the metal, their 10 holding power near the middle would not be equal to that near the supporting members. The degree of curvature required will, of course, vary according to the materials used and the distance between supports.

In order that the invention might be fully understood, the details of an embodiment thereof have been thus specifically described; but

20 What I claim is:—

1. In a device of the character described, the combination of two jaws movable relative to each other, of standards supporting one of the said jaws, a plurality of members 25 pivoted to said standards and carrying the other jaw, a plurality of levers pivoted to said standards and links pivoted at one end to said levers and at their other ends to said pivoted members carrying the other jaw.

2. In a device of the character described, 30 the combination with two jaws movable relative to each other, of means adapted to control positively the movements of said jaws and to lock them in closed position, said controlling and locking means embodying 35 an upright standard supporting one of said jaws, a member pivoted to said standard and carrying the other jaw, said pivoted member extending below its pivotal connection with said standard, a lever pivoted at one end to 40 said standard, a link operatively connecting said lever with the lower end of said pivoted member and adapted to cause the line passing through its points of connection with said lever and said pivoted member to approach the pivotal point of said lever on said standard as said jaws are moved together, and means for securing said jaws to a bedstead.

In testimony whereof I have signed my 50 name to this specification, in the presence of two subscribing witnesses, on this 3rd day of April, A. D. 1909.

JOHN T. COWLES.
